CLAIM

The ornamental design for a boot as shown and described.

DESCRIPTION

FIG. 1 is a perspective view of a boot showing my new design.

FIG. 2 is a left-side elevation view thereof.

FIG. 3 is a right-side elevation view thereof.

FIG. 4 is a front elevation view thereof.

FIG. 5 is a rear elevation view thereof; and,

FIG. 6 is a top elevation view thereof.

The broken lines in the drawing represent portions of the boot that form no part of the claim. This includes any portions of the boot that appear to depict stitching.
